C. F. Baxter

UNITED STATES PATENT OFFICE.

CHARLES F. BAXTER, OF BOSTON, MASSACHUSETTS.

FURNACE.

Specification of Letters Patent No. 28,730, dated June 19, 1860.

To all whom it may concern:

Be it known that I, CHS. F. BAXTER, of Boston, in the county of Suffolk and State of Massachusetts, have invented a new and 5 useful Improvement in Steam and Hot-Air Furnaces, Combining the Uses and Advantages of Both a Steam-Furnace and Hot-Air Furnace in One; and I do hereby declare that the following is a full and exact de-
10 scription.

In Figure 1, A, represents a double cylinder steam generating and gas burning fire-pot, to line stove, range, or furnace. Its form may be round, oval or otherwise, to 15 correspond to its use. B, is the inlet water pipe. C, is the water level, and allows a few inches for a steam chamber. D, is a pipe to convey steam for cooking; and to radiators, for warming rooms, &c. E, E, 20 are two pipes passing through the fire-pot and base, to admit air to consume the gases generated in fire chamber F.

Fig. 2, is a vertical section of fire-pot A, with corresponding letters.

Fig. 3, represents a "steam" generating and "hot-air furnace," incased with brick, or portable, in the usual hot-air chamber H, and radiating its hot air, by flues I, to adjacent rooms. The cold air is admitted to 25 chamber H, through openings at the bottom thereof. G, is an oven, for baking and roasting. A, is the double cylinder steam generating fire-pot, lining the cylinder J,

and inclosing the fire F. E, E, are two pipes admitting fresh warm air through the 35 fire-pot and base, to consume the gases generated by the fire F. B, is the inlet water pipe. C, is the water level. D, the steam pipe, to convey steam to radiators to warm rooms, not accessible to hot-air flues, and also 40 to convey steam to other vessels for culinary purposes.

I do not claim a double cylinder fire-pot or "water jacket;" a "steam furnace;" or "hot-air furnace"—they are all in use, and 45 well known—separately. I disclaim all, except the combination.

I claim—

1. The combination of a double cylinder steam generating fire-pot with pipes E, E, 50 substantially as described, and for the purposes set forth.

2. The arrangement of the steam generating fire pot E, to stand apart from but within the inner wall J of the hot air chamber 55 H, so that the exterior surface of the fire pot will be constantly surrounded by the hot products of combustion, as shown.

3. The arrangement of the oven G, directly above the fire pot E, but within the inner 60 wall J, of the hot air chamber H, as herein shown.

CHS. F. BAXTER.
